UNITED STATES PATENT OFFICE.

CHARLES LOUIS CRABB, OF NEW YORK, N. Y.

APPARATUS FOR RENDERING DRAWINGS AND DOCUMENTS TRANSPARENT AND WATERPROOF.

No. 808,901.

Specification of Letters Patent.

Patented Jan. 2, 1906.

Application filed April 6, 1905. Serial No. 254,171.

To all whom it may concern:

Be it known that I, CHARLES LOUIS CRABB, a citizen of the United States, and a resident of the borough of Brooklyn, in the city and State of New York, have invented a new and useful Improvement in Apparatus for Rendering Drawings and Documents Transparent and Waterproof, of which the following is a specification.

10 The object of this invention is to render drawing - paper or similar material permanently transparent and waterproof after drawings or writings have been made thereon and to render indelible such drawings or writings 15 when made with lead - pencil or other ordinarily erasable drawing or writing material.

The process consists in passing the sheets of drawing or documents to be rendered permanently transparent, waterproof, and indelible 20 through a hot solution having for its body paraffin or other suitable transparent and waterproof material and while they remain heated and coated and saturated with said solution subjecting them to a calendering operation.

25 The apparatus which constitutes the invention consists in the combinations hereinafter described and claimed, in which the principal elements are a bath in which the treating solution is contained and heated, a heated calendering-chamber in communication with said bath and containing calender - rollers, and a sheet - carrier for carrying the sheets to be treated first through the bath and afterward through the calendering-chamber and delivering them in a finished condition.

The apparatus is represented in the accompanying drawings, in which—

Figure 1 represents a plan with the cover of the calendering-chamber removed and the carrier in section; Fig. 2, a longitudinal vertical section in the line 2 2 of Fig. 1; Fig. 3, a transverse vertical section of the calendering-chamber in the line 3 3 of Fig. 1; Fig. 4, a vertical section of the calendering-chamber in the line 4 4 of Fig. 1; Fig. 5, a longitudinal vertical section of the upper portion of the sheet-carrier and the cover of the calendering-chamber; Fig. 6, a side view of the tension-adjusting device for the sheet-carrier; Fig. 7, 45 a plan view of a spreader applied to the sheet-carrier.

50 10 designates the bath, and 11 the calendering-chamber, represented as composed of a single casting, but separated by curtain-like partition 12, which extends downward to with-

in a short distance from the bottom of the bath. The chamber 11 is represented as having a removable cover 11*.

13 18 are the calendering-rollers, of highly-polished metal, having their journal-boxes 14 horizontally adjustable in slides 15 16, which are secured to the bottom of the calendering-chamber by screws 17. These slides, one on each side of the chamber, consist each of a base 15 and a cap - plate 16, secured thereon by screws 18. Between the several journal-boxes in each slide there are coil-springs 19, exerting a constant tendency to separate the rollers, and between the boxes of the front and rear rollers and the ends of the slides there are coil-springs 20, the said springs being kept in place by concave projections 21 on the boxes and on the ends of the slides. Through each end of each slide there is screwed a screw 23, serving to exert and adjust pressure on the rollers to bring them more or less close to each other, according to the thickness of the paper or material to be calendered and the calendering-pressure required. These screws pass freely through holes provided for them in the ends of the chamber.

24 24 designate the sheet-carrier consisting of two members each composed of a pair of narrow flexible endless metal bands arranged one pair or member at each side of the apparatus and the two bands of each pair or member lapping and adapted to run one outside of the other in one of two grooves 25, formed in the calendering-rollers near the ends thereof. The said bands are carried by rollers 26 27, arranged in bearings above the bath and the calendering-chamber, and rollers 28 29 in bearings on the bottom of the bath, and they run from the bath under the partition 12 into the calendering-chamber and over, under, and between the calendering-rollers, thence through an opening in the cover of the chamber to and over the roller 27. For making the tension of the bands self-adjusting the said roller 27 is carried by slides 30, running in slideways 31 on the top of the chamber-cover 11*, and is connected by a pulling spring 32 with a lug 33 on said cover. The roller 26 is made to constitute a feed - roller by being furnished with pin-like teeth which enter holes 33*, provided for them in the bands. The said roller 26 is represented as furnished with a hand-crank 34 for the purpose of turning it to move the carrier through the bath and the calendering-chamber.

About midway between the rollers 26 27 there is arranged a spreader which is common to the two members of the carrier and which is represented as consisting of two parallel rods 35, running across and between the two bands of both carrier members and carried by two small plates 36, on which are journals 37, running in boxes 37* on the top of the chamber. On one of these journals is a small hand-lever 38 by which to turn the spreader to the position shown in Fig. 2, in which the rods 35 are side by side between the bands, and so allow those parts of each pair which are above the bath and above the calendering-chamber 15 to come near enough together, as shown in Fig. 2, to take a sheet or to the position shown in Fig. 5, by which a greater separation is produced between those parts of the bands to permit the introduction and removal of the sheet. On each of the said journals 37 there is a small toothed sector or pinion 39, which engages, as shown in Fig. 6, with a toothed rack 40 on the roller-slide 30 at the corresponding side of the apparatus. When the spreader 20 is turned to the position shown in Fig. 5 to spread the bands, the slides 30 and roller 27 are drawn toward the roller 26 sufficiently to compensate for the spreading.

The bath and the calendering-chamber may 30 be separately heated by any suitable means. For this purpose in the example represented there are gas-burners 41 42, one under the bath, another under the chamber.

For carrying out the process any transparent 35 waterproof liquid or solution not volatile at atmospheric temperature may be used; but what I have used successfully and at present prefer is a solution of paraffin in alcohol in the proportion of about twelve parts, by 40 weight, of paraffin to one part of alcohol.

The operation of the apparatus is as follows: The bath being filled with the solution to a suitable depth and both it and the calendering-chamber being heated to a sufficient degree 45 the bands of the two members of the carrier are spread apart, as shown in Fig. 5, and a sheet to be treated is introduced between those parts of them which are between the spreader and the feed-roller 26. The spreader is then 50 turned to the position shown in Fig. 2 to let the bands of the carrier come nearer together, and the carrier is set in motion by turning the crank 34 to carry the sheet down into the bath and slowly through the solution therein, and 55 thence coated and saturated with the solution, through the calendering-chamber on and between the calendering-rollers 13, which are set in motion by the carrier-bands running on them. From the calendering-chamber the 60 coated, saturated, and calendered sheet is carried upward until it arrives in the carrier at a position between the roller 27 and the spreader, when the movement of the carrier is stopped and the spreader is turned to sepa-

rate the carrier-bands, as shown in Fig. 5, and 65 the sheet taken from between the bands.

One of the advantages resulting from the use of this apparatus is that working mechanical drawings may be made in lead-pencil on the heaviest drawing-paper, and after having been thus treated the pencil-lines become so permanently fixed as not to be liable to rub out, the paper becomes transparent, and the drawings resemble those made in ink on tracing-cloth, inasmuch as clear and distinct blue-prints may be taken from them as from such tracings. This does away with the expensive work of inking in the pencil-drawing or making tracings therefrom.

What I claim as my invention is—

1. In an apparatus for treating drawings and documents, the combination of a bath, a heating-chamber and calendering-rollers therein, and a sheet-carrier for passing sheets through said bath and thence through said chamber 85 and between said rollers.

2. In an apparatus for treating drawings and documents, the combination of a bath, a heating-chamber and calendering-rollers therein, and endless bands which serve the two purposes of carrying sheets through said bath and chamber in contact with said rollers and driving said rollers.

3. In a calendering-chamber, the combination with calendering-rollers and journal-boxes therefor, of slides containing the several journal-boxes, springs within said slides between said boxes and screws screwing through said slides for the adjustment of said boxes and the rollers therein.

4. In an apparatus for treating sheets of paper or other material, the combination of a bath, a heating-chamber and calendering-rollers therein, a sheet-carrier composed of endless bands in lapping pairs running through said bath and chamber and on said rollers, and a separating-spreader applied between the bands of each pair.

5. In an apparatus for treating sheets of paper or other material, the combination of a bath, a heating-chamber and calendering-rollers therein, a sheet-carrier composed of endless bands in lapping pairs running through said bath and chamber and on said rollers, a spreader applied between the bands of said carrier, a spring-actuated tension-roller applied to said carrier, a slide carrying said tension-roller, and gearing between said slide and the spreader for simultaneously adjusting said roller and the spreader.

In testimony that I claim the foregoing as my invention I have signed my name, in presence of two witnesses, this 3d day of April, 1905.

CHAS. LOUIS CRABB.
